UNITED STATES PATENT OFFICE.

NICK G. PAPPAS, OF HANNA, WYOMING.

AEROPLANE.

1,395,204.

Specification of Letters Patent. Patented Oct. 25, 1921.

Application filed March 17, 1921. Serial No. 453,056.

To all whom it may concern:

Be it known that I, NICK G. PAPPAS, a citizen of Greece, residing at Hanna, in the county of Carbon and State of Wyoming, have invented certain new and useful Improvements in Aeroplanes, of which the following is a specification.

This invention relates to certain new and useful improvements in aeroplanes, particularly of that type embodying wing propellers, although the several detail features of the invention are capable of general application.

The primary object of the invention is to provide improved actuating means for the wing propeller which shall be efficient in operation as well as of simple construction and of a durable nature.

A further object of the invention is to provide an aeroplane embodying oppositely extending pairs of planes, with improved means for simultaneously tilting the same upon horizontal axes extending transversely of the fuselage for effectively controlling the ascent or descent of the machine.

Further objects will become apparent as the nature of the invention is better understood and the same consists in the novel form, combination and arrangement of parts hereinafter more fully described in connection with the accompanying drawings, in which like reference characters designate corresponding parts throughout the several views.

35 In the drawings,

Figure 1 is a top plan view of an aeroplane constructed in accordance with the present invention with a portion of the planes broken away,

Fig. 2 is a side elevational view of the device shown in Fig. 1,

Fig. 3 is a front elevational view thereof, partly broken away,

Fig. 4 is a horizontal sectional view of the empennage taken upon line IV-IV of Fig. 2,

Fig. 5 is a longitudinal sectional view of the machine shown in Fig. 1 and taken upon line V-V of Fig. 6,

Fig. 6 is a horizontal longitudinal sectional view taken upon line VI-VII of Fig. 5,

Fig. 7 is a transverse sectional view through the wing propellers and taken substantially upon line VII-VII of Fig. 1,

Fig. 8 is a vertical sectional view partly broken away and taken upon line VIII-VIII of Fig. 7,

Fig. 9 is a vertical longitudinal sectional view through the planes upon line IX-IX of Fig. 1,

Fig. 10 is a fragmentary vertical sectional view taken upon line X-X of Fig. 9,

Fig. 11 is a plan view of a modified form of wing propeller which may be employed and

Fig. 12 is a sectional view taken upon line XII-XII of Fig. 11.

Referring more in detail to the several views, the present invention contemplates improvement of that type of aeroplane which embodies a fuselage or body 5 having suitable launching or landing means including supporting wheels 6 mounted under the forward end of the fuselage 5 and provided with an empennage 7 at its rear end which includes a pair of horizontal rigidly mounted and spaced tail planes 8 between which is movable the vertically disposed rudder 9 which is swingingly mounted upon a vertical axis 10. The support for the upper tail plane 8 may be of any suitable form, but preferably comprises upright rods 11 fixed to and extending upwardly from the rear portion of the fuselage 5 and braced by suitable guy wires 12 extending to the rear of the canopy or roof 13 of the fuselage. Any desired means may be provided for swinging the rudder 9, but the latter preferably consists of a flexible member 14 having one end attached to an arm 15 extending to one side of the hub portion 16 of the rudder 9, and extending downwardly through suitable openings 17 in the fuselage and under guide pulleys 18 to a point forwardly of the entrance opening 19 which is usually provided for admitting the operator within the fuselage. The flexible member passes around a drum 20 at this latter point and then rearwardly through further guides 18 and another opening 17 in the fuselage where the other end of the flexible member is attached to another arm 21 extending to the other side of and from the hub 16. The drum 20

is fixed upon a vertical shaft 22 suitably journaled in an upright position at the forward portion of the body 5, and this drum 20 is disposed near the floor of the body while a handle 23 is fixed to the shaft 22 adjacent its upper end so as to be within con-

100
105
110

venient reach of the operator for oscillating said shaft and correspondingly swinging the rudder 9 in the desired direction for effecting steering of the machine to the right 5 or left in the usual manner.

The present machine is provided in the extreme forward end of the body 5 with a suitable supporting means 24 for the propelling motor 25 whose driven shaft 26 extends forwardly through the forward end of the body 5 and has a suitable rotary propeller 27 associated therewith for effecting forward propulsion of the machine. The shaft 26 also extends rearwardly a slight 10 distance and has a bevel gear 28 fastened upon its rearwardly extending portion, said bevel gear 28 meshing with another bevel gear 29 which is suitably secured upon a transversely disposed shaft 30 which is journaled in a horizontal position forwardly of the shaft 22. A sprocket wheel 31 is loosely mounted upon one end portion of the shaft 30 and is adapted to be clutched or unclutched from said shaft by means of a sliding clutch 15 member 32 which is movable by a horizontal hand lever 33 pivoted in a horizontal position upon the upper end of an upright 34 and extending rearwardly beneath the handle 23. A second transverse shaft 35 is journaled horizontally of the body 5 rearwardly of the shaft 22 and said shaft 35 is rotatably geared to the shaft 30 by means of a sprocket chain 36 which passes around the sprocket wheel 31 and also around another sprocket wheel 37 fixed upon the shaft 30 within the body 5. The shaft 35 extends through the side of the body and outwardly some distance beyond the latter where it has crank disks 38 fixedly secured upon the extreme end portions thereof, the crank disks 38 being operatively connected to the opposed wing propellers 40 by means of pitman rods 39 which are eccentrically pivoted on the disks 38 as at 41 and pivotally attached to the wings as at 42. The wing propellers are each shaped to conform broadly to the outline of a bird's wing as shown clearly in plan in Fig. 1 and their inner edges are pivotally mounted upon the body 5 as at 43 so that the wing propellers may swing vertically through the operation of the pitmen 39 for exerting a lifting force upon the aeroplane, it being noted that the pitmen will effect a flapping motion or oscillation to the wing propellers when the shaft 35 is rotated upon starting of the motor 25 and throwing in of the clutch 32. The action of the wings 40 and the upward movement of the same is greatly facilitated 20 by the provision of compression springs 44 between the wing propellers and suitable abutments 45 which are rigid with the sides of the body 5 and which are disposed outwardly of the pivots 43. As shown, the wing or wing propellers 40 consist of a

suitable frame covered with fabric or the like, and the same may take the form shown in Fig. 1 or the modified form shown in Figs. 11 and 12 wherein provision is made for lessening the air resistance to the upward movement of the wings and for automatically presenting a maximum surface to the air for propulsion purposes upon downward movement thereof. As shown in these figures, the above function is accomplished 70 by constructing the wing of a main frame like portion 46 with a large central opening 47 normally closed by a panel 48 which is disposed beneath the frame portion 46 and hinged to the latter along one edge as at 49, 75 the hinge 49 being of the spring type to normally hold the panel in closed position as shown in Fig. 5, and the spring of the hinge being of such strength as to permit opening of the panel upon upward movement of the wing in response to the force of the air resistance.

A pair of superposed shafts 50 and 51 are journaled in a horizontal position transversely through the body 5 between the shafts 22 and 30, and upon each end of the shafts 50 and 51 at the opposite sides of the body is fixed a plane 52 so that a pair of spaced planes is provided at each side of the body and movable with the shafts 50 and 51 80 for varying the angle of said planes as indicated in Fig. 9 for directing the descent or ascent of the machine as will be apparent. Means is provided for simultaneously rotating the shafts 50 and 51 in the same direction 85 for tilting both of the planes of both pairs of planes in the same general direction and so as to maintain at all times the normal parallel relation of the planes of each pair, and the same includes a depending crank 100 arm 53 upon the shaft 50 and an upwardly extending crank arm 54 upon the shaft 51 respectively connected by links 55 and 56 with the opposite ends of a bar or lever 57 which is mounted upon a horizontal axis 110 adjacent the lever 33 and which is provided with a rearwardly extending operating handle 58 which is disposed in convenient reach of the operator. It will thus be seen that when a downward movement is given to the handle 58, a rearward pull is exerted upon the link 55 and a forward movement is imparted to the link 56 so as to rotate shafts 50 and 51 for tilting the planes 52 downwardly, while an upward movement of the handle 58 120 will reverse this operation.

The planes 52 of each pair are rigidly connected in proper spaced relation by braces 59 vertically disposed between said planes and having brackets upon the ends of the same 125 as at 60 which project into the planes as shown in Fig. 9 and have the shafts 50 and 51 freely extended therethrough.

In operation, the motor 25 is thrown into operation in any usual or well known man- 130

- ner and forward movement is imparted to the aeroplane through the operation of the propeller 27, and when the latter has attained a desired speed, the planes 52 are tilted upwardly and the clutch 32 is thrown in for causing driving of the shaft 35 and through the connection of the latter with the propeller wings 40, the latter are rapidly reciprocated and the propeller 27 is thereby assisted in the lifting and the propulsion of the machine. By swinging the handle or lever 23 in the desired direction, the rudder 9 may be swung to steer the aeroplane to the right or left as occasion may require.
- From the foregoing description, it is believed that the construction and operation as well as the advantages of the present invention will be readily understood and appreciated by those skilled in the art.
- Minor changes may be made without departing from the spirit and scope of the invention as claimed.

What is claimed as new is:

In an aeroplane, a pair of superposed horizontal shafts, a fuselage having said shafts horizontally journaled therethrough, planes fixed upon the ends of said shafts at opposite sides of said fuselage, means operable from within the fuselage for simultaneously rotating said shafts in the same direction for tilting said plane, said means for simultaneously rotating the shafts including oppositely extending crank arms fixed to said shafts, a vertical lever having its intermediate portion pivoted upon a horizontal axis, a link connecting each end of said lever with one of said crank arms, and means to rock said lever.

In testimony whereof I affix my signature in presence of two witnesses.

NICK G. PAPPAS.
